UNITED STATES PATENT OFFICE.

EDWARD L. CZARNIECKI, OF ASPINWALL, PENNSYLVANIA.

DESIGN FOR A BOX-BLANK.

SPECIFICATION forming part of Design No. 34,276, dated March 26, 1901.

Application filed June 15, 1899. Serial No. 720,704. Term of patent 14 years.

To all whom it may concern:

Be it known that I, EDWARD L. CZARNIECKI, a citizen of the United States, residing at Aspinwall, in the county of Allegheny and State of Pennsylvania, have invented and produced 5 a new and original Design for a Box-Blank, of which the following is a specification, reference being had to the accompanying drawings, in which—

10 Figure 1 is a plan view of my design, and Fig. 2 a section on the line II II of Fig. 1.

The leading feature of my design is in the shape, configuration, and embossing of the box-blank. The blank 1 consists of the rectangular portion 2, having extending centrally therefrom at one side the rectangular portion 3. Extending from the side 8 to the side 10 of the portion 3 of the blank and of 15 equal length are the straight embossed portions 12, of which three are formed on the portion 3 of the blank and the fourth forms the dividing-line between the two portions 2 and 3 of the blank. Extending from the side 4 to the side 6 of the portion 2 of the blank

are the straight embossed portions 13. Extending from the sides 8 and 10 of the portion 3 transversely across the portion 2 are the straight embossed portions 14, and from each of the corners of the portion 2 to the junctions of the embossed portions 13 and 14 extend short straight embossed portions 15. The configuration of each of the embossed portions 14 and 15 is similar to that of the portions 12 and 13, as indicated on the drawings.

The whole forms an integral unique article of a distinctive and novel character.

I claim—

15 The design for a box-blank as described and shown.

In testimony whereof I have hereunto set my hand, in the presence of two witnesses, at Pittsburg, county and State aforesaid, this 14th day of June, A. D. 1899.

EDWARD L. CZARNIECKI.
